UNITED STATES PATENT OFFICE.

FREDERICK WILLIAM STARK, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A TEAPOT OR SIMILAR ARTICLE.

Application filed November 6, 1924. Serial No. 11,303. Term of patent 14 years.

To all whom it may concern:

Be it known that I, FREDERICK W. STARK, a citizen of the United States, residing at Meriden, in the county of New Haven and State of Connecticut, have invented a new, original, and ornamental Design for a Teapot or Similar Article, of which the following is a specification, reference being had to the accompanying drawing, forming part thereof.

I claim:

The ornamental design for a teapot or similar article as shown.

FREDERICK WILLIAM STARK.

Witnesses:

A. M. KNAPP,
L. A. WASHER.
